UNITED STATES PATENT OFFICE.

FRANK CHALLONER, OF OSHKOSH, WISCONSIN.

SHINGLE-SAWING MACHINE.

SPECIFICATION forming part of Letters Patent No. 555,148, dated February 25, 1896.

Application filed May 8, 1893. Serial No. 473,392. (No model.)

To all whom it may concern:

Be it known that I, FRANK CHALLONER, of Oshkosh, in the county of Winnebago and State of Wisconsin, have invented certain new and useful Improvements in Spalt-Droppers for Shingle-Sawing Machines; and I do hereby declare that the following is a full, clear, and exact description of the invention, which will enable others skilled in the art to which it pertains to make and use the same, reference being had to the accompanying drawings, and to the letters of reference marked thereon, which form a part of this specification.

My invention relates to that class of shingle-sawing machines in which the shingle bolts or blocks are held and moved horizontally in a rotary carriage over one or more horizontal saws located below the carriage. Its main objects are to facilitate the dropping or discharge from the machine of the spalts or residuum of the shingle bolts or blocks, and in the attainment of that end to employ fluid-pressure for the operation of the spalt-dropper, and to arrange the trip mechanism for controlling the operation of the spalt-dropper for the several block-receptacles in the carriage within constant reach of the operator.

It consists of certain peculiarities in the construction and arrangement of the component parts of the machine hereinafter particularly described and pointed out in the claims.

In the accompanying drawings like letters designate the same parts in the several figures.

Figure 1 is a plan view of a rotary shingle-sawing machine to which my improvements are applied. Fig. 2 is an enlarged front elevation and partial vertical section on the line 2 2, Fig. 1, of the spalt-dropper. Fig. 3 is a side elevation and partial vertical section of the same on the line 3 3, Fig. 1. Fig. 4 is a medial longitudinal section of the cylinder and its associated valve-case on a still larger scale; and Figs. 5 to 8, inclusive, are detail views, on an enlarged scale, of the trip mechanism by which the operation of the spalt-dropper is controlled, Fig. 5 being a front elevation, Fig. 6 a side elevation, and Fig. 7 a horizontal section on the line 7 7, Fig. 5.

Referring to Fig. 1, A represents a portion of the horizontal rotary carriage, which is

supported upon the upper end of a central vertical shaft *a*, and is formed with a series of block receptacles or openings *a' a'*, provided in the usual manner with dogs (not shown) for holding the shingle-blocks therein.

B B are two horizontal saws fixed to the upper ends of vertical arbors located just below the carriage on opposite sides of the machine.

C is a spider supported upon the upper ends of columns *c* and *c'* from a base *C'* and constituting therewith the frame of the machine.

D D are the tilt-tables located adjacent to the cutting-edges of the saws a little below the plane thereof and arranged to give the proper inclination to the shingle-blocks as they are dropped thereon to cause the butts and points of the shingles to be taken alternately from opposite ends of said blocks.

E and E' are curved horizontal ways concentric with the carriage and supported approximately in the plane of the saws between said saws and the tilt-tables.

F is a vertical carriage-driving shaft, which is geared in the usual manner (not shown) with the carriage and with a horizontal pulley-shaft *G*.

The foregoing parts are shown and described for the purpose of explaining more clearly the construction and operation of my improvements, but in themselves constitute no essential part of my invention, and may be of any construction or arrangement suitable for use in connection with such improvements.

The curved way E on the front side of the machine next to the operator is formed with an opening of sufficient length to permit the passage of a shingle block or spalt of the greatest width the machine is designed to receive. It is provided with and normally closed by a plate or slide *H*, which constitutes a continuation thereof, and is movable horizontally in a radial direction upon ways *h h*, adjustably attached to and supported by the spider C, as shown in Fig. 2. It is connected by links *i i* with arms *i' i'* on a horizontal rock-shaft I, by which both ends are caused to move together and are prevented from binding in their ways.

J is a cylinder preferably arranged in a

horizontal position in which it may be conveniently supported upon the spider C, as shown. It is provided with a piston j, which is connected by the piston-rod j' with a bracket 5 attached to the under side of the slide H. The cylinder is formed or provided on one side with a cylindrical valve-case K, in which is fitted a piston-valve having two heads k k, mounted upon a rod k'. The valve-chamber and cylinder are connected near their ends by passages j² j³, as shown in Fig. 4, which have branches j³ j³ opening into cavities next to or near the cylinder-heads. The ends of the branches j³ opening into the cylinder are normally closed 10 by inwardly-opening valves j⁴ j⁴. The valve-case is also formed with exhaust-openings k² k² near its ends and an intermediate supply or inlet opening k³, which is connected by a pipe k⁴ with the compressed-air reservoir 15 c' or other source of fluid-pressure. It will be observed that one of the hollow supporting posts or columns c' of the frame is utilized in this case for the compressed-air or fluid-pressure reservoir.

25 Referring to Figs. 5 to 8, inclusive, in connection with Fig. 1, L is a trip-wheel mounted next to the operator's table or within easy reach of the place usually occupied by the operator upon the front end of a horizontal shaft l, which extends across the machine and is provided at its rear end with a worm-wheel l', meshing with a worm f on the carriage-driving shaft F, through which connections said trip-wheel is rotated isochronously with 30 the carriage. The trip-wheel is provided with a series of radially-movable trip-pins l² l², corresponding in number and arrangement with the number and arrangement of the block-receptacles in carriage A. These pins are held 35 in place either in normal or abnormal position in which they may be left by the operator or by the restoring-incline by springs l³.

40 m m' are inclines formed on bars M M, which are pivoted at one end to fixed arms projecting 45 on opposite sides of a sleeve N, and are connected at the opposite end by links m² m² with a cross-head n on a rock-shaft n' passing loosely through said sleeve and provided at its opposite end with an arm n². The incline m is located outside of the rim of the trip-wheel L in or adjacent to the path of the outer ends of the trip-pins l² l² when they are projected outwardly in normal position, and the incline m' is located between the rim and 50 center of said wheel in or adjacent to the path of the inner ends of said trip-pins when they are projected inwardly into abnormal position. The arm n² is connected by a rod n³ with one arm of a bell-crank lever O, the 55 other arm of which is connected with the valve-rod k', as shown in Figs. 1, 2, and 3.

P is a fixed incline located in the path of the inner ends of the trip-pins l² and arranged to automatically return them into normal position after they have acted upon the incline m' to open the spalt-dropper.

My improved machine operates as follows: The reservoir c' being supplied with compressed air or any other suitable fluid medium under pressure, while the trip-pins l² l² are all projected outwardly, as shown in Fig. 5, the valve k k will be held in the position in which it is shown in Fig. 1, thereby admitting the actuating medium into the inner end of cylinder J and holding the piston j and the slide H with which it is connected in normal position, closing the opening in the curved way E. When the operator wishes to drop a spalt from any of the block-receptacles a' a' in the carriage, he thrusts the corresponding trip-pin l² inwardly at any time in its passage from the fixed incline P to a point adjacent to the incline m'. The inner end of said trip-pin being thus projected into the path of said incline m' and held in place by the contiguous spring l³ engages and moves said incline inwardly, turns the cross-head n with which it is connected into the position in which it is shown in Figs. 6 and 7, and thereby shifts the valve k k through the connections hereinbefore described into the position in which it is shown in Fig. 4. The actuating medium is now admitted from the valve-chamber through the passage j² and branch j³ at the outer end of the cylinder, between the piston j and outer cylinder-head, and the passage j² at the other end of the cylinder is opened to exhaust through the opening k² at the inner end of the valve-case. The piston is thereby instantly moved inwardly, carrying the slide H with it and presenting an opening underneath the receptacle from which the spalt is to be discharged. The piston j is cushioned at the end of its stroke in both directions by the air or fluid medium contained in the ends 90 of the cylinder between the openings of passages j² j² thereinto and the cylinder-heads, the valves j⁴ j⁴ closing the intermediate ports of the branches j³ j³, except for the admission into the cylinder of the actuating medium. 95 Upon clearing the incline m' the trip-pin l², which has just shifted the spalt-dropper, encounters the incline P and is thrust outwardly thereby into its normal position. The next succeeding trip-pin, which is in normal position, engages the incline m and turns the cross-head n back into the position in which it is shown in Fig. 1, restoring the valve, piston and slide H to their normal positions.

100 It is obvious that spalts may be discharged from any number of block-receptacles in succession by pushing in the corresponding trip-pins l² l². It will also be observed that the trip-pins being at all times within reach of the operator may be set to operate the 105 spalt-dropper at any point in their passage, whatever may be the position of the block-receptacle in the carriage from which the spalt is to be discharged. This will be found a great convenience and advantage over the 110 arrangement heretofore employed, in which the trips were applied to the carriage, one

for and adjacent to each block-receptacle, and only accessible during a small portion of its circuit while it passed the operator.

Various changes in details of construction 5 and arrangement of the component parts of the spalt-dropper may be made within the intended scope of my invention.

I claim—

1. In a shingle-sawing machine, the combination with a rotary carriage provided with a series of block-receptacles, of a movable block-support located below said carriage, a separate trip-wheel of smaller diameter than the carriage provided with a series of movable trips corresponding in number and position with the block-receptacles in said carriage and all constantly within reach of the operator, and actuating connections arranged to shift said support and controlled in operation by said trips, substantially as and for the purposes set forth.

2. In a shingle-sawing machine, the combination with a rotary carriage provided with a series of block-receptacles and spalt-dropping mechanism, of trip mechanism controlling the operation of said spalt-dropping mechanism and comprising a separate trip-wheel of smaller diameter than the carriage rotated isochronously with said carriage and provided with a series of trips corresponding in number and arrangement with the block-receptacles of said carriage and all constantly within reach of the operator, substantially as and for the purposes set forth.

3. In a shingle-sawing machine, the combination with a rotary carriage provided with a series of block-receptacles and a spalt-dropper, of trip mechanism controlling the operation of said spalt-dropper and consisting of a separate trip-wheel of smaller diameter than the carriage connected and arranged to be isochronously rotated with said carriage and provided with a series of radially-movable slides or pins corresponding in number and arrangement with the block-receptacles of said carriage and all constantly within reach of the operator, and a movable incline connected with the spalt-dropper, substantially as and for the purposes set forth.

4. In a shingle-sawing machine, the combination with a rotary carriage provided with a series of block-receptacles and spalt-dropping mechanism, of separate trip mechanism consisting of a wheel of smaller diameter than the carriage capable of isochronous rotation with the carriage and provided with a series of trips within constant reach of and movable by the operator into abnormal position, and a movable part connected with the spalt-dropping mechanism and arranged to be shifted by said trips when they are moved into abnormal position, substantially as and for the purposes set forth.

5. In a shingle-sawing machine, the combination of a rotary carriage provided with a series of block-receptacles, of spalt-dropping mechanism and trip mechanism consisting of

a trip-wheel separate from and of smaller diameter than the carriage capable of isochronous rotation with said carriage and provided 70 with a series of trips constantly within reach of the operator and movable into abnormal position, two inclines movable alternately into the path of said trips and connected with said spalt-dropping mechanism, substantially as 75 and for the purposes set forth.

6. In a shingle-sawing machine, the combination with a rotary carriage provided with a series of block-receptacles, of spalt-dropping mechanism and separate trip mechanism 80 consisting of a wheel of smaller diameter than the carriage capable of isochronous rotation with said carriage and provided with a series of trips constantly within reach of the operator and movable into abnormal position, a 85 movable part connected with the spalt-dropping mechanism and projecting normally into the path of said trips when they are in abnormal position, and an incline arranged to automatically restore said trips to normal 90 position, substantially as and for the purposes set forth.

7. In a shingle-sawing machine, the combination of a rotary carriage provided with a series of block-receptacles, of spalt-dropping 95 mechanism and trip mechanism consisting of a wheel separate from and of smaller diameter than the carriage geared to rotate isochronously with said carriage and provided with a series of trip-pins or slides movable 100 radially therein and all constantly within reach of the operator, an oscillatory head located adjacent to said wheel and connected with the spalt-dropping mechanism, and two inclines connected with said head on opposite 105 sides of its axis and movable alternately, one into range with the outer ends of said pins or slides when projected outwardly, and the other into range with the inner ends of said pins or slides when projected inwardly, substantially as and for the purposes set forth.

8. In a shingle-sawing machine, the combination with a rotary carriage provided with a series of block-receptacles, of an open way located underneath said receptacles and provided with a radially-movable slide, substantially as and for the purposes set forth.

9. In a shingle-sawing machine, the combination with a rotary carriage provided with a series of block-receptacles, of an open way 120 located underneath said receptacles and provided with a radially-movable slide, and a rock-shaft provided with parallel arms which are connected by links with said slide and cause a like simultaneous movement of its 125 ends, substantially as and for the purposes set forth.

10. In a shingle-sawing machine, the combination of a rotary carriage provided with a series of block-receptacles, a way located below said carriage and provided with a radially-movable section, a cylinder arranged radially with respect to the carriage and provided with a piston which is connected by its rod

directly with said movable section, and a valve controlling the operation of said piston, substantially as and for the purposes set forth.

11. In a shingle-sawing machine, the combination with a rotary carriage provided with a series of block-receptacles, of spalt-dropping mechanism comprising a movable support located at one side of the machine below said carriage, a cylinder provided with a piston which is connected with said support, and a valve-chamber connected with opposite ends of said cylinder and provided with a controlling-valve, and trip mechanism comprising a trip-wheel of smaller diameter than the carriage connected and arranged to rotate isochronously with the carriage and provided with a series of trips movable into abnormal position and constantly within reach of the operator, and a movable part connected with said valve and having projections arranged to be moved alternately into the path of said trip, substantially as and for the purposes set forth.
12. In a shingle-sawing machine, the combination

nation with a rotary carriage having a series of block-receptacles, and a way located below the path of said receptacles and provided with a radially-movable section, of a spalt-dropping device, comprising a cylinder arranged radially with respect to the carriage, 30 a piston fitted therein and connected by its rod directly with the movable section of said way, a valve-case provided with a valve and connected by passages with opposite ends of the cylinder, each passage having two ports 35 in the cylinder, one nearer the cylinder-head than the other, and inwardly-opening valves normally closing the two ports nearest the cylinder-head, substantially as and for the purposes set forth.

In testimony that I claim the foregoing as my own I affix my signature in presence of two witnesses.

FRANK CHALLONER.
